DESIGN FOR A TOY

Robert E. Boyse and Stuart W. Bradford,
Saginaw, Mich.

Application September 15, 1944, Serial No. 115,309

Term of patent 3½ years

(Cl. D34—15)

To all whom it may concern:

Be it known that we, Robert E. Boyse and Stuart W. Bradford, citizens of the United States, both residing at Saginaw, county of Saginaw, State of Michigan, have invented a new, original, and ornamental Design for Toys, of which the following is a specification, reference being had to the accompanying drawing, forming part thereof.

The figure is a side perspective view of a toy, showing our new design.

Portions of the design are lined to indicate color.

We claim:

The ornamental design for a toy, as shown and described.

ROBERT E. BOYSE.
STUART W. BRADFORD.
